Assistant Examiner—John Windmuller

(57) **CLAIM**

The ornamental design for a remote control, substantially as shown and described.

DESCRIPTION

FIG. 1 is a perspective view of a remote control as seen from the front, top and right side;

FIG. 2 is a front view thereof;

FIG. 3 is a rear view thereof;

FIG. 4 is a right side view thereof; the left side view being a mirror image of the right side view;

FIG. 5 is a top view thereof; and,

FIG. 6 is a bottom view thereof.

The broken lines in the figures delineate portions of the remote control that form no part of the claimed design.
